UNITED STATES PATENT OFFICE.

LYMAN P. WHITCHER, OF PROVIDENCE, RHODE ISLAND.

SIGN-BRACKET FOR AUTOMOBILES.

1,091,553.

Specification of Letters Patent. Patented Mar. 31, 1914.

Application filed March 31, 1913. Serial No. 757,739.

To all whom it may concern:

Be it known that I, LYMAN P. WHITCHER, a citizen of the United States, residing at Providence, in the county of Providence and 5 State of Rhode Island, have invented certain new and useful Improvements in Sign-Brackets for Automobiles, of which the following is a specification.

My invention relates to sign holders for 10 automobiles, and has for its essential objects the provision of means for applying a sign to the front portion of an automobile, and more particularly to the radiator thereof; to provide a structure that is capable of being 15 simply and cheaply manufactured, and one that is capable of facile adjustment to any size of sign, and whose attaching means is certain, firm, and adapted to all circumstances.

20 To the above ends essentially my invention consists in such parts and combinations of parts as fall within the scope of the appended claims.

In the accompanying drawings which form 25 a part of this specification:—Figure 1 is a front elevation of my holder or bracket, applied to the front of an automobile radiator, the latter being shown with its lower portion broken away, Fig. 2, a side elevation of 30 the same, Fig. 3, a front elevation of the bracket removed from the radiator, Fig. 4, a plan of the same, Fig. 5, an enlarged side elevation of the portion of one of the threaded rods, showing in side elevation an adjusting disk and bearing disk having parts 35 broken away, and Fig. 6, a section on line $\alpha\alpha$ of Fig. 3.

Like reference characters indicate like parts throughout the views.

40 In the drawings A indicates the radiator of an automobile in conjunction with which my invention is in the present instance to be described. The detailed construction of the radiator may be of any well-known type, 45 and is provided with the usual interstices or openings a .

My holder consists of a body portion B which is preferably in one piece, cut in the first instance from a strip of metal and bent 50 into the desired shape. In detail the body is angular in cross section, comprising a horizontal portion b and a vertical or downwardly directed portion b' . At the ends of the horizontal portion are rearwardly directed curved arms C terminating in upwardly turned circular lugs c provided with

perforations c' . The vertical portion of the body is provided with downwardly directed curved arms D whose ends are upwardly bent forming hooks d. Integral with an intermediate portion of the portion b' of the body is a rearwardly directed inclined arm E provided at its end with a circular attaching lug e having a perforation e' . The portion b of the body is provided with an opening f, and passing loosely through this is a screw G provided with a head g and a threaded shank g' . This screw passes through an opening h in a plate H comprising a horizontal portion h parallel with the portion b , and having upon its forward portion a vertically disposed hook I whose beak i is downwardly directed; and has a nut J upon the shank g' of the screw, and by means of this member H may be vertically 75 adjusted. A number plate K may rest in the upturned hooks d and is clamped in such position by the vertical downwardly directed hook I operated by the screw G and nut J. By the screw and nut adjustment my 80 device is adapted to accommodate number plates of varying sizes.

The attaching portion of the bracket consists of rods L passing through the opening c' in the lugs c provided with screw heads l bearing against the face of the lugs, and provided also at their rear ends with screw threads l' . The rods L pass through the openings a in the radiator and carry upon their rear ends disks or nuts M provided 90 with threaded openings m adapted to engage the threads l' of the rods. It is preferable that there be mounted upon the rods L adjacent the lugs c and the disks M washers or disks N and O respectively consisting of some soft compressible material which accommodate the attaching parts more readily to the irregular surfaces of the radiator. A similar rod P passes through the opening c' in the arm E and is 100 provided with a screw head p and a screw thread p' . Upon this rod is a disk Q similar in all respects to the disks M, and there is provided also the washer or bearing disks q and q' similar in structure to the washers 105 N and O. In attaching the supporting portion of the bracket the nuts or disks M and Q are turned upon the threaded rods approximately to their final position with relation to the rear surface of the radiator and 110 then by a screw driver the heads l and p of the rods are finally tightened thus forc-

ing the several washers into tight engagement with the face of the radiator.

What I claim is:—

1. In a sign bracket for automobiles, the combination of a body provided with an opening, rearwardly-directed arms integral with the ends of the body, lugs upon the arms, downwardly-directed arms upon the body, upwardly-directed hooks upon the last-mentioned arms, a plate provided with an opening in alinement with the said opening of the body, a vertically-disposed downwardly-directed hook upon the plate in the vertical plane of the first-mentioned hooks, a screw passed through the openings in the body and plate, and a nut upon said screw.
2. In a sign bracket for automobiles, the combination of a body composed of a single piece of material angular in cross section and comprising a horizontal portion and a depending portion, arms integral with the horizontal portion, attaching lugs upon the ends of the arms, an inclined arm integral with the horizontal portion, an attaching lug upon the last mentioned arm, depending arms integral with the depending portion

of the body, upwardly directed hooks upon the last mentioned arms, a plate supported upon the horizontal portion of the body and provided with a hook, downwardly directed in the vertical plane of the last mentioned hooks, and means for vertically adjusting the plate relatively to the body.

3. In a sign bracket for automobiles, the combination of a body, horizontal arms upon the body, lugs upon the arms provided with perforations, a rearwardly inclined arm upon the body, a lug upon the arm provided with a perforation, arms depending from the body, hooks upon the ends of the last mentioned arms, rods passing loosely through the perforations in the lugs provided with threads, heads upon the rods engaging the outer surfaces of the lugs, and disks provided with threads adapted to engage the threads upon the rods.

In testimony whereof I have affixed my signature in presence of two witnesses.

LYMAN P. WHITCHER.
